UNITED STATES PATENT OFFICE.

HENRY A. HOESCHEN AND JOHN D. WEAR, OF OMAHA, NEBRASKA.

LOCK.

Application filed December 30, 1926. Serial No. 157,991.

This invention relates to locks, and particularly to a lock of the coin controlled type.

It is an object of this invention to produce a lock that will remain in locked condition

5 until tripped by an object exerting pressure on the tripping means, and preferably the object required for the tripping operation will be a coin of certain denomination. As illustrating the present embodiment of the 10 invention, the money required is supposed to be a half dollar coin, although obviously, the device can be proportioned so that the tripping mechanism could be made to operate in conjunction with coins of other diameters 15 and sizes.

It is a further object of this invention to provide novel means whereby the shackle of the lock will be retained in locked position by instrumentalities which will also serve to 20 guard against the escape of the coin after the lock has been manipulated to release the object which it secured, so that by this invention, a lock may be applied to a device for securing an automobile or any other 25 property, and when the property is reclaimed by the insertion of the coin of the required denomination and the lock is manipulated to release the property, the lock becomes effective to retain the coin against intended or 30 accidental withdrawal.

It is furthermore an object to produce a lock of this character comprising comparatively few and inexpensive parts.

With the foregoing and other objects in 35 view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in elevation of 45 the exterior of a lock embodying the invention;

Figure 2 illustrates a sectional view thereof with the lock secured in its stage of manipulation;

50 Figure 3 illustrates a sectional view showing the parts in the second stage of manipulation where the coin has released the detent of the shackle and secured the coin guard;

Figure 4 illustrates in elevation of a fragment of the shackle in its relation to an ejector;

Figure 5 illustrates a top plan view of the lock with the key about to be inserted;

Figure 6 illustrates a sectional view of the lock on the line 6—6 of Fig. 2;

Figure 7 illustrates a sectional view of the lock on the line 7—7 of Fig. 3 with the coin omitted;

Figure 8 illustrates a sectional view of the lock on the line 8—8 of Fig. 2; and

Figure 9 illustrates a perspective view of the dog.

In the present embodiment of the invention, a lock casing 10 is provided having a cavity in its inner face for the operating mechanisms, to be presently explained, and the casing may have any appropriate face plate 11, and these parts may be secured together in any appropriate way by rivets or the like. One end of the casing has a seat 12 for an end 13 of the shackle 14, whereas the opposite end of the shackle reciprocates in an opening 15 of the casing and extends downwardly into the cavity at one side or edge thereof. The casing has a rib 16 that stands in spaced relation to the inner wall 17, and this forms a way in which an extension 18 of the shackle is slidable. The extension has an annular shoulder 19 which serves to guide the shackle in the cavity, and the said shoulder is engaged by a flange 20 of the rib 16, whereby the axial movement of the shackle is limited.

A spring 21 is seated in the cavity and encircles the extension of the shackle. The 90 spring bears against the shoulder and exerts pressure to move the shackle outwardly and to retain the shoulder in engagement with the flange when the device is unlocked. The shackle is also provided with a beveled surface 22 terminating in a shoulder 23 to be engaged by the end 24 of a dog 25, which dog is pivotally mounted on a stud 26 within the casing. The dog serves to hold the shackle against movement when it is in engagement with the shoulder, although the dog will be manipulated to release the shackle, as will presently appear.

A spring 27 is anchored to the dog and it bears against an inner wall of the cavity at the top thereof, as shown in Fig. 3, and this spring is effective, under certain conditions, to swing the dog on its pivot in order that it will engage the shoulder of the shackle to secure the lock. An arm 28, preferably of 105 relatively rigid character compared with the spring 27, is also anchored to the dog, and

the said arm has a surface 29 which is adapted to be engaged by a coin 30 when the lock is to be released and the coin is to be secured in the lock, it being the intention of 5 the inventors that the arm shall be in the path of travel of the coin in order that the pressure of the coin on the arm will overcome the tension of the spring 27 and move the dog on its pivot to disengage the said dog 10 from the shoulder of the shackle.

As a means for manipulating the coin, a yoke 31 is provided and it is slidable in the lower end of the lock casing and it is of a size that will fit between the rib 16 and the 15 opposite inner wall of the casing. The yoke or stirrup has a shoulder 32 at one side adapted to be engaged by the shoulder of the dog after the coin has been inserted and has swung the dog from engagement with the 20 shackle. Figure 3 shows the dog locked to the yoke and retaining it in position to hold the coin secure in the casing. When the coin is to be released, a key 33 may be manipulated to force the dog from engagement with 25 the yoke and the yoke will therefore be permitted to slide outwardly to release the coin. The yoke is pressed normally outwardly by a spring 34 on a post 35 and the said post extends into an aperture 36 in the yoke. The 30 spring 34 bears against the inner end of the yoke and normally exerts pressure on it to force it outwardly so that after the dog disengages the yoke, the spring causes the ejection or partial ejection of the coin. The yoke is limited in its movement by reason of the 35 projection 39 on the yoke engaging a stop 40 on the case.

In Fig. 2 when the lock is locked to secure 40 property, there is a clearance 37 between the coin seat of the yoke and the lower end of the lock casing, through which the coin is introduced into the casing, and when so introduced, the coin is forced further into the casing by pressure on the yoke, which moves 45 the yoke inwardly and forces the coin against the arm to overcome the tension of the spring 27 in order that the dog will be manipulated. To facilitate the introduction of the coin, the surface 38 of the yoke is 50 rounded and it will therefore cam over this rounded surface as it is pressed into the lock casing.

From an inspection of the drawing and 55 the foregoing description, it will be apparent that after the lock is secured to guard property, it cannot be manipulated by the key, since any pressure of the key on the dog will more firmly seat the dog in engagement with the shackle, and it is only by imparting 60 movement to the dog through pressure applied on the arm that the dog will be caused to release the shackle.

The spring 21 has one end anchored to the casing and the opposite end anchored to a part of the shackle, and by this means, the 65 shackle is turned after the end 13 is freed from the seat 12.

We claim:

1. A coin controlled lock consisting of a 70 lock case, a shackle therein, a detent for holding the shackle in locked position, means associated with the detent and operative by pressure of a coin to disengage the detent from the shackle, means for exerting pressure on the coin to operate the detent, and means whereby the detent engages the coin moving means and holds it against movement to retain the coin in the lock. 75

2. A coin controlled lock consisting of a 80 lock case, a shackle therein, a detent for holding the shackle in locked position, means associated with the detent and operative by pressure of a coin to disengage the detent from the shackle, means for exerting pressure on the coin to operate the detent, means 85 whereby the detent engages the coin moving means and holds it against movement to retain the coin in the lock, and means for operating the shackle when released by the 90 detent. 90

3. In a coin controlled lock, a case, a shackle having one end projecting therein, a dog for engaging the shackle, means for oscillatably mounting the dog, a spring associated with the dog for holding it normally in engagement with the shackle, a coin engaged element in the case associated with the dog, means for forcing a coin into the case against the said element for moving the dog, coacting means between the dog and the last mentioned means for retaining said last mentioned means in position to retain the coin in the case, said dog being adapted to be released by a key. 100

4. In a coin controlled lock, a case, a shackle slidable therein, a dog pivotally mounted in the case and adapted to engage the shackle for retaining the shackle against movement, a spring exerting pressure on the 110 dog to hold it normally in operative position with relation to the shackle, a member connected to the dog adapted to be engaged by a coin for exerting pressure to move the dog against the action of the spring, a member 115 slidable in the case and adapted to engage the coin and move it against the said member, means on the dog for engaging said means to retain it in the case, the said dog being adapted to be moved by a key, and means for moving the said coin engaging device outwardly to release the coin. 120
